UNITED STATES PATENT OFFICE

113,246

DESIGN FOR A GEAR SHIFT KNOB OR SIMILAR ARTICLE

Deas Trahan, Long Island City, N. Y., assignor
of one-half to Bernard Berneau, Long Island
City, N. Y.

Application December 5, 1938, Serial No. 81,579

Term of patent 3½ years

To all whom it may concern:

Be it known that I, Deas Trahan, a citizen of the United States, residing at 29-14 39th Avenue, Long Island City, in the county of Queens and State of New York, have invented a new, original, and ornamental Design for a Gear Shift Knob or Similar Article, of which the following is a specification, reference being had to the accompanying drawing, forming a part thereof.

Figure 1 is a top plan view of a gear shift knob, showing my new design; and

Figure 2 is an elevational view thereof.

I claim:

The ornamental design for a gear shift knob or similar article, as shown.

DEAS TRAHAN.
